US0D1025498S

(12) **United States Design Patent** (10) **Patent No.:** **US D1,025,498 S**
(45) **Date of Patent:** **** Apr. 30, 2024**

(54) **KNEE PAD**

(71) Applicant: **Milwaukee Electric Tool Corporation**,
Brookfield, WI (US)

(72) Inventors: **Trent T. Bauters**, West Allis, WI (US);
Scott M. Hangartner, Richfield, WI (US);
Emelie E. Troedson, Seattle, WA (US)

(73) Assignee: **Milwaukee Electric Tool Corporation**,
Brookfield, WI (US)

(**) Term: **15 Years**

(21) Appl. No.: **29/868,453**

(22) Filed: **Dec. 2, 2022**

Related U.S. Application Data

(62) Division of application No. 29/730,276, filed on Apr. 2, 2020, now Pat. No. Des. 973,970.

(57) **CLAIM**

We claim the ornamental design for a knee pad, as shown and described.

DESCRIPTION

FIG. 1 is a front perspective view from above of a first embodiment of a knee pad showing our new design; FIG. 2 is a rear perspective view from above of the claimed design of FIG. 1; FIG. 3 is a rear perspective view from below of the claimed design of FIG. 1; FIG. 4 is a second rear perspective view from below of the claimed design of FIG. 1;

FIG. 5 is a front view of the claimed design of FIG. 1; FIG. 6 is a rear view of the claimed design of FIG. 1; FIG. 7 is a left side view of the claimed design of FIG. 1; FIG. 8 is a right side view of the claimed design of FIG. 1; FIG. 9 is a top view of the claimed design of FIG. 1; FIG. 10 is a bottom view of the claimed design of FIG. 1; FIG. 11 is a front perspective view from above of a second embodiment of a knee pad;

FIG. 12 is a rear perspective view from above of the claimed design of FIG. 11; FIG. 13 is a rear perspective view from below of the claimed design of FIG. 11; FIG. 14 is a second rear perspective view from below of the claimed design of FIG. 11;

FIG. 15 is a front view of the claimed design of FIG. 11; FIG. 16 is a rear view of the claimed design of FIG. 11; FIG. 17 is a left side view of the claimed design of FIG. 11; FIG. 18 is a right side view of the claimed design of FIG. 11;

(Continued)

FIG. 19 is a top view of the claimed design of FIG. 11; and, FIG. 20 is a bottom view of the claimed design of FIG. 11.
